UNITED STATES PATENT OFFICE.

WILLIAM KOCH, OF NEW YORK, N. Y., ASSIGNOR OF ONE-HALF TO CHARLES HYAMS, OF SAME PLACE.

DESIGN FOR A QUILTING-PATTERN FOR SKIRTS.

SPECIFICATION forming part of Design No. 16,176, dated July 21, 1885.

Application filed June 30, 1884. Term of patent 7 years.

To all whom it may concern:

Be it known that I, WILLIAM KOCH, of the city, county, and State of New York, and a citizen of the United States, have invented and produced a new and original Design for Quilting Linings and Skirts, of which the following is a specification, reference being had to the accompanying drawing, forming part thereof.

10 The invention consists in the pattern hereinafter described.

The accompanying drawing is a plan view showing the quilted pattern stitched on the fabric of the garment in accordance with this invention.

15 A represents parallel rows of scalloped or waved lines, the scallops of one line not being in contact with the scallops of the other,

and B represents rows of stitched circles, the circumferences of the circles in one row being in contact with the circumferences of the circles of another row, and so on throughout the series of rows.

What I claim as my design, and desire to secure by Letters Patent, is—

25 The pattern for quilting linings and skirts, consisting of series of stitched circles B, with their circumferences in contact, and rows of waving or scalloped lines A, each line being equally distant from another, substantially as 30 described and shown.

WILLIAM KOCH.

In presence of—

G. M. PLYMPTON,
D. A. CARPENTER.
